ELASTIC FLUID MECHANISM

Rudolph Birnmann, Newtown, Pa., assignor to De Laval Steam Turbine Company, Trenton, N.J., a corporation of New Jersey

Filed May 10, 1954, Ser. No. 428,627

20 Claims. (Cl. 253—39)

This invention relates to elastic fluid mechanism and has particular reference to improved designs of impellers, diffusers and turbines; the invention being, in part, directed to the design of the bounding surfaces of the elastic fluid passages of such devices. The invention relates also to an improved type of gas turbine.

This application is in part a continuation of my application, Serial Number 38,995, filed July 16, 1948, which was in part a continuation of my application, Serial Number 614,791, filed September 6, 1945, now Patent 2,623,357, dated December 30, 1952.

One object of the present invention is the embodiment of novel principles of design in flow passages for elastic fluid in which changes of its thermodynamic state are being effected. In accordance with this object there is provided a novel type of compressor embodying one or more impellers and associated diffusers. Also within the scope of this object is the provision of a novel type of turbine, the same basic principles applying to all of these fluid-handling elements. Basically, this aspect of the invention comprises the attainment of designs to satisfy the requirements of high efficiency, the distribution of work input and output to avoid aerodynamic overloading while properly taking into account the laws governing stability of flow, and the securing of other conditions to provide maximum efficiency and to avoid losses. In brief, these ends are accomplished by the design of either rotating or stationary passages in conformity with the laws required for stable, three-dimensional, flow, i.e., flow which fulfills the differential equations for the flow of an elastic fluid without separation from its boundaries.

In design in accordance with the invention for the attainment of these objectives it is found that, in the case of rotary devices such as compressors and turbines, the blades, if made in the form of single continuous surfaces extending from entrance to exit of the elastic fluid, will generally deviate very substantially from radial condition and hence would be subjected to enormous centrifugal stresses in high speed devices to which the invention is particularly applicable. Accordingly, a further object of the invention is to provide blading for such devices consistent with the fundamental desired principles but having a construction such that centrifugal stresses are kept within proper bounds. This object is attained by either providing rows of blades which do not deviate to a non-permissible degree from radial condition but, in fact, serve to support each other to provide a blade structure of adequate rigidity and strength, or by adopting for the blade surfaces (in the case of single blades) a three-dimensional-type surface which is characterized by possessing at least one, and preferably not less than two, radial anchoring lines which impart sufficient strength to the blades so that non-radial portions of the blades resulting from the flow requirements can be safely tolerated.

A further object of the invention is concerned with the construction of high speed rotors for compressors and turbines involving improved hub construction so that light weight may be achieved consistently with high me-

2

chanical strength. Hubs in accordance with the invention are in the form of convex shells, the stresses in which are, at any point, substantially only in tension with the result that light weight construction is secured. In the improved construction thermal stresses are minimized as compared with the conventional discs.

The invention also provides a method of producing blades which are designed entirely from the point of view of the aerodynamic principles embodied in the invention, and are not restricted due to considerations of manufacturing, and it provides a novel method of producing such blades and fastening them to the rotor hubs.

The invention also serves to provide very desirable small discharge angles. As is well known in compressor design, small discharge angles result in high efficiency and desirable characteristic curves of performance. However, such discharge angles have heretofore not been attainable without involving design difficulties. With small discharge angles a higher degree of reaction is obtained, or, in other words, a much greater percentage of the total pressure rise is produced in an impeller as a direct result of centrifugal effect, which is a highly efficient process, and a smaller percentage of the total pressure rise must be obtained in a relatively inefficient diffuser. In accordance with the invention, substantially more than 50% of the total static pressure rise is obtained in the impellers, the remainder being secured in the diffusers, which, in accordance with the invention are made unusually efficient, this high diffuser efficiency being achieved by so designing the impellers in accordance with the present invention that the flow leaving the impeller and entering the diffuser is unusually homogeneous, that is, at equal distances from the center of rotation there is little or no difference in the direction and magnitude of the velocity components, resulting in minimizing the so-called mixing losses arising from momentum transfer.

A further object of the invention is a provision of a novel type of gas turbine in which, among other features, the compressor blading and turbine blading are carried by a common hub with various attendant advantages which will hereafter be set forth.

These and other objects of the invention particularly relating to details of construction and operation will become apparent from the following description read in conjunction with the accompanying drawings in which:

Figure 1 illustrates in axial section the assembly of the parts of a five stage compressor constructed in accordance with the invention;

Figure 2 is an elevation showing the inlet side of the second stage impeller of Figure 1;

Figure 3 is an axial section showing in particular the construction of the hub of the second stage impeller of Figure 1, this construction being generally typical of that involved in the other impellers illustrated in Figure 1;

Figure 4 is an elevation of the inlet side of a modified form of impeller illustrating in particular the formation of vanes in two sections;

Figure 5 is an axial section of the impeller of Figure 4;

Figure 6 is a perspective diagram illustrative of certain geometrical elements involved in the design of an impeller;

Figure 7 is an axial view of the matter illustrated in Figure 6;

Figure 8 is a diagram illustrating a meridional projection of Figure 6, with an auxiliary diagram at the upper left portion of this figure looking in the direction of the arrow to show the true value of the angle γ ;

Figure 9 is a diagram explanatory of certain of the steps in design procedure hereafter set forth;

Figures 10A and 10B are diagrams illustrating certain considerations involved in two types of approach flow to an impeller;

Figures 11, 12, 13 and 14 are further diagrams explanatory of design procedure;

Figure 15 is a chart showing various expressions and equations referred to in the following description of design principles;

Figure 16 is a diagram illustrating certain dimensions involved in an expression given for vanes at (7) in Figure 15;

Figure 17 is a diagram explanatory of another fashion in which vanes or blades provided in accordance with the present invention may be defined;

Figure 18 is an elevation, partly in axial section, illustrating a gas turbine constructed in accordance with the invention, the turbine being particularly designed for constant speed drive;

Figure 19 is an enlarged section on the plane indicated at 19-19 in Figure 18 showing the hollow construction of a turbine blade; and

Figure 20 is an elevation, partly in axial section, illustrating another form of gas turbine constructed in accordance with the invention and particularly designed for variable speed drive.

In order to provide an understanding of the invention the description will first be applied to the design of a five stage compressor illustrated in assembly in Figure 1. A rotor is built up of a series of individual rotor elements, one for each stage, designated generally as 2, 4, 6, 8 and 10. These are held together axially by means of an axial rod 12 as indicated. The air passages through the stages have their circumferential outer limits defined by a housing 14 with which the blading of the impellers has suitable small clearances and which supports the vanes of the various diffusers. The housing 14 is held in proper concentricity with the rotor by a rigid structure 14', the housing 14 being free to slide axially within this structure. The blading of the first stage impeller is indicated generally at 16, that of the second stage impeller at 18, that of the third stage impeller at 20, that of the fourth stage impeller at 22, and that of the fifth stage impeller at 24. The various associated diffusers have their vanes indicated generally at 26, 28, 30, 32 and 34. These diffuser vanes are secured to the housing 14. In advance of the first stage impeller there are provided directing vanes indicated at 36 so arranged as to impose free vortex flow (or other desired flow as hereafter pointed out) on the air entering the first stage impeller. These vanes are conventional and are of the type used to provide free vortex flow in axial flow compressors.

Bearings 38 and 40 mount the rotor of the compressor.

Referring to Figures 2 and 3 which show the impeller 4 of the second stage, the hub comprises a convex portion 42 in the form of a body of revolution supported by discs 44 and 46 and provided with a cylindrical strut or compression member 48. The fore and aft extensions 50 and 54 of the hub are toothed as indicated at 52 and 56 for interlocking with the preceding and succeeding impellers. As will be noted from Figure 3 the hub is made in two sections for purposes of simplicity of construction. These two sections are brazed together to form the complete hub. As will be pointed out in greater detail hereafter the hub is made in the form illustrated so that the peripheral portions thereof when loaded by the vanes are substantially only in tension to secure a light weight but nevertheless extremely strong construction. The impeller vanes 18 which will also be discussed in greater detail hereafter are secured to the inlet side of the hub and have inlet and outlet edges respectively indicated at 58 and 60. In Figure 3 various radial planes are designated by Roman numerals and the intercepts of these planes with one of the vanes 18 are correspondingly designated in Figure 2 to give an indication of the shape of the vane.

In Figures 2 and 3 each of the vanes consists of a single continuous section from the inlet edge to the outlet edge. In some cases, as will be more fully pointed out hereafter, the vanes are desirably made up of two or more

sections and for the purpose of illustrating this Figures 4 and 5 show another impeller in which this construction is adopted. The impeller generally indicated at 62 has a convex portion 64 carried by the discs 66 and 68 which are joined by the cylindrical compression strut 70. Extensions 72 and 74 are provided with teeth 76 and 78 for interlocking with adjacent impellers as in the case of the modification previously described. Each of the vanes of this impeller comprises two sections 80 and 81 which as indicated in Figure 4 overlap each other and may be connected together for mutual support where they meet, the connection being effected, for example, by welding. Alternatively, the vane sections may merely support each other by leaning against each other, this resulting in excellent vibration damping. The inlet and outlet edges of the first section 80 are indicated at 83 and 85 while the inlet and outlet edges of the second section 81 are indicated at 87 and 89 respectively. In Figure 5 various radial planes are designated by Roman numerals and the intercepts of these planes with one of the vanes are indicated in Figure 4 by corresponding Roman numerals.

Theoretical considerations show that the maximum efficiency of the impeller passages will result when these passages are of the mixed flow type, i.e., when in the progress from inlet to outlet the flow of the elastic fluid being handled has a suitable radially outward component of motion with discharge at an average radius greater than the average radius at the inlet. This is in contrast to the design of axial flow impellers in which the mean radius of flow is substantially constant. It is also in contrast with ordinary centrifugal impellers in which the axial length of path is a minimum consistent with smoothly changing the direction of flow from an axial approach to a discharge with substantially no axial component of motion. (However, various aspects of the invention are applicable to impellers of both of the last mentioned types to improve their efficiencies.)

Referring now to Figures 6, 7 and 8, the impeller passages are interiorly bounded by a surface of revolution indicated at 84 and constituted by the hub surface, this surface of revolution, in the case of the present second stage impeller to which these figures relate, extending from a substantially cylindrical portion at the inlet to a substantially cylindrical portion at the outlet with smooth variation of curvature between the inlet and the outlet, the latter of which is at a substantially greater radius than the inlet. It may be here noted that the fact that this surface of revolution becomes substantially cylindrical at both inlet and outlet is not of major significance in the present design and, as will be pointed out hereafter, this approach to the cylindrical condition is by no means necessary and, in fact, is not involved at the outlet from the fifth stage. The cylindrical condition when it exists at the inlet and the outlet is merely a matter of desirability when the inlet is from an approach flow which does not have a substantial radial component of motion and when the outlet is arranged for delivery to a succeeding stage requiring a radially inward deflection of flow. Since work on the elastic fluid in an impeller should be accomplished when the flow has no radially inward component of motion, the cylindrical inlet and outlet conditions merely represent limits; at both inlet and outlet the surface of revolution such as 84 could be tangent to cones diverging in the direction of axial progress of the elastic fluid.

The external circumferential boundary of the passages is defined by a surface of revolution indicated at 86 generally similar in its governing conditions to the surface 84. This surface 86 follows in a general way the surface 84, generally having greater radial spacing from the latter surface at its inlet than at its outlet. The surface 86 is defined by the inside of the casing with which the blading of the impeller has slight clearance.

In brief, the inner and outer circumferential boundaries for the flow are subject to rather arbitrary choice gov-

erned by considerations of preceding and succeeding devices, efficiency (for example in securing a maximum percentage of pressure gain in an impeller due to centrifugal effect), cross-sectional area sufficient to handle the desired flow, smooth turning of flow, Mach number, mechanical strength of the rotor, etc. As will become evident, hereafter, these boundaries are treated as arbitrarily assumed in the approach to the design of the blading in the cases of compressors, diffusers and turbines.

By virtue of the impeller blading the elastic fluid is caused to have between the surfaces of revolution 84 and 86 paths of flow relative to the impeller along stream lines, one of which is indicated in Figures 6, 7 and 8 at S. It may be assumed, with small error, that the flow is axially symmetrical so that any stream line, if rotated about the axis of revolution of the impeller, would, in any position, coincide with another stream line. Accordingly, if a stream line were rotated about the axis the locus of its successive positions would be a surface of revolution such as indicated at 88, any point of which would be on a particular stream line which would lie wholly in this surface. The surfaces such as 88 will be designated hereafter as stream surfaces. Considering a particular point P on the stream line S illustrated in the figures under consideration, an axial plane through the point P will intersect the stream surface 88 in a line M which will be called a meridian line of the stream surface. As will be hereafter apparent the variations of an angle γ along any meridian line is definitive of all of the similar stream lines on any corresponding stream surface, and consequently of the shapes of the vanes extending along the stream lines, and this angle will be clear from Figures 6 and 8 in which it is illustrated as the angle between the tangents at any point P to the stream line and to the meridian line of the stream surface passing through that point. The upper left hand portion of Figure 8 illustrates the projection which gives rise to a true value of the angle γ . The angle, it will be noted, lies in a plane which is tangent to the stream surface at the point P. Before departing from consideration of these figures there may also be noted, as indicated on Figure 8, the angle λ which is the angle between the tangent plane just mentioned and the axis of rotation. It is, of course, the angle of slope of a meridian line of a stream surface with reference to the axis of rotation. As used hereafter, the Z axis is taken along the axis of rotation, being positive in the direction of the flow. The origin of reference is taken at O, arbitrarily, as used hereafter, at the axial position of the inlet face of the impeller. The angle ϕ_T indicated in Figure 7 is the total angle about the axis of rotation subtended by a stream line from its inlet end to its outlet end. ϕ , Figure 7, is a coordinate angle corresponding to any point such as P. Its origin is arbitrary, as will more fully appear in its use hereafter.

As applied to an impeller, the invention involves the determination first, of the stream line S which should exist between inlet and outlet of an impeller for the proper transfer of energy to the flow for assumed conditions of operation and for a choice, arbitrary to some extent as indicated above, of the inner and outer circumferential boundaries of the flow passages. Secondly, there are to be determined the vanes which will actually impose flow along these stream lines and which, for all practical purposes, must lie along the stream lines at any point, i.e., every element of area of a vane must, subject to consideration of vane thickness and proper fairing of inlet and outlet, consist of a surface which is the locus of a group of adjacent stream lines.

It may be noted that the curvature of the inner and outer circumferential boundaries will be taken into account in determining the vane shape; and also taken into account is the nature of the approach flow to the vanes; for example, in some cases the flow to an impeller, as in the case of some first stage impellers, may have no radial component of motion, as indicated for example in Figure

10A, whereas in the case of succeeding stages, or in the case of the first stage illustrated in Figure 1, the flow has a curvature in its meridional projection into an axial plane, as indicated in Figure 10B. The resulting blade angles for these two cases differ substantially.

Involved in the first step is the satisfaction of the well known three-dimensional laws of flow and thermodynamics of elastic fluids, i.e., given the other boundary conditions the stream lines must be determined as proper solutions of the differential equations expressing these laws. In the present exposition, there will be omitted the lengthy and intricate proofs that the succession of steps involved in the present design actually satisfies these laws; instead there will be set forth those steps involved in determining the stream lines which actually represent, in the form of a method of successive approximation, the procedure for solution of the various equations mathematically stating the laws.

Various types of flow have been investigated, and it has been found that vortex flow proves to be especially advantageous for the described type of compressor: for a given limiting Mach number the twist of the blades along any radius can be kept smaller than for any other flow. It happens that vortex flow has the advantage of allowing a relatively easy calculation compared with other types of flow. The following calculation procedure is based on vortex flow; i.e., along orthogonal lines there is assumed to exist a constant product $c_u \cdot r$, a constant total energy and a constant entropy (c_u being the whirl component and r being the radius). The foregoing is to be taken as the definition of vortex flow as that term is used herein.

In cases where the Mach numbers are not considered as excessively high, other flow patterns may be applied, favoring small or zero blade twist, regularly distributed mass flow over the channel width, and/or regularly distributed degree of reaction, etc.

Assuming that hub and tip contours have been chosen in accordance with the principles given above, which contours as will now be evident define surfaces of revolution 84 and 86 bounding the elastic fluid passages, with the meridian lines of at least one of said surfaces deviating substantially from parallelism with the axis, the design then proceeds with the assumption of certain constants as follows:

The vortex strength at the inlet, $(c_u \cdot r)_{in}$, c_u being the whirl component and r the radius at any point of the inlet.

The vortex strength at the inlet, $(c_u \cdot r)_{in}$, c_u being the same quantities are evaluated at the outlet.

The angular velocity, ω , of the impeller. (This is zero in the case of stationary passages.)

(Considerations such as the desired work input per stage, maximum permissible tip speed, etc., together with such a choice of $(c_u \cdot r)_{in}$ as will result in low Mach numbers, small twists, etc. will determine these constants.)

The inlet temperature and the inlet pressure.

The weight flow, G.

The constriction coefficient ϵ .

The adiabatic efficiency of the impeller (or diffuser). This may be taken, for original calculation, as that of known impellers of similar capacity.

The design then involves steps as follows, reference being made to the various equations given in Figure 15.

Meridians, which may be defined as the intersections of stream surfaces with axial planes, e.g. M of Figure 6, are tentatively assumed as at 91, 93 and 95, Figure 9. The intersections of an axial plane with the surfaces 84 and 86 provide fixed inner hub and outer tip meridians, as indicated. It is convenient to choose these on an assumption of division into four equal parts of the mass flow through the impeller, and they are so indicated in this figure. (It may be noted that this choice is rather arbitrary in view of the adoption of the method of suc-

cessive approximations which leads ultimately to determination of actual meridians.)

Tentative orthogonals to the meridians are plotted at those locations where it is desired to determine the proper blade angles. In Figure 9 such tentative orthogonals are indicated at 90, 92, 94, 96, 98 and 100, those at 90 and 100 corresponding to the inlet and outlet ends of a blade. (When the term orthogonal is used herein it will be understood to refer to an orthogonal to the meridians in an axial plane.) Based on these orthogonals, the different steps which will now be given lead to the determination of new tentative meridians. As will be hereafter pointed out, these tentative meridians are then used for the drawing of a new set of orthogonals and the procedure is repeated until convergency of the process leads to a sufficiently accurate approximation.

The meridians of the hub and tip contours being known and fixed, their curvatures are determined either graphically or analytically. Let:

k_0 =the curvature of the meridian of the hub contour at the base of the tentative orthogonal being considered, taken positive for a portion of the meridian concave towards the axis of rotation;

k_1 =the curvature of the meridian of the tip contour at the outer end of the tentative orthogonal being considered, with the same sense of sign;

s =the distance from the hub to the point being considered measured along the orthogonal passing through the point;

Δs =the total length of said orthogonal being considered;

k' is an expression equal to

$$\frac{k_1 - k_0}{2\Delta s}$$

c_m =the meridian velocity at the point being considered, i.e., the component of the absolute velocity in the direction of the meridian of the stream surface through the point; and

c_{m0} =the meridian velocity at the hub end of the orthogonal through the point.

The foregoing quantities are related in accordance with Equation 1 of Figure 15. It should be noted that c_m and c_{m0} are not separately known at this point in the calculation, by their ratio is given by Equation 1.

In the case of an impeller, a curve of N versus l is now assumed, Figure 11, in which N is the work input reached in the impeller from the entrance through the distance l measured along an estimated mean meridian such as 93 in Figure 9. (It is to be noted that the total N is known from the assumed $(c_u \cdot r)_{in}$ and $(c_u \cdot r)_{out}$; see Equation 2.)

It may also be noted that, in the case of an impeller having substantially axial inlet and substantially axial discharge, as in Figure 9, by reason of design for a variation of N with l having a small slope at the inlet and outlet, there will exist a substantial region in the vicinity of the inlet and in the vicinity of the outlet where there is no substantial change of N . Accordingly, the inlet and outlet edges may deviate quite arbitrarily from radial planes with substantial uniformity of N nevertheless existing along each edge. For this reason radial inlet and outlet edges may be assumed as in Figure 9 for purposes of calculation, though actually these edges may, in the impeller, be non-radial.

For the assumed inlet conditions, including an assumption that throughout the extent of the inlet the conditions lie on an adiabatic line, there may now be plotted a curve of specific volume v against the expression

$$N - \frac{c^2}{2gJ}$$

wherein N is evaluated at the inlet, c is the absolute velocity and the variable for the plot, g is the acceleration due to gravity, and J is the mechanical equivalent of heat.

Such a curve is obtainable from the usual air tables. A curve of specific volume v against the expression

$$N - \frac{c^2}{2gJ}$$

is now plotted for the outlet conditions assuming an efficiency for the impeller derived from experience, e.g. 90%, and assuming that throughout the extent of the outlet the conditions lie on an adiabatic line. These two curves differ so little from each other that interpolation for points other than at the inlet and outlet can be carried out with sufficient accuracy.

The value of c at any particular point must be determined. For this, c_{m0} for the orthogonal through the point under consideration is assumed on a trial basis. Then Equation 1 gives c_m for the point. The whirl component c_u is now determined using Equation 2 in which it will be noted all of the right hand terms are known. Using these values of c_m and c_u , c is determined from Equation 3.

Now using the value of c_m for any point and the plots for v , mentioned above, the weight flow G may be calculated from Equation 4, all of the right hand expressions in which are known, ϵ being assumed to be, for example 0.95 or more or less depending upon an assumption of blade thickness, number of blades to be used, and boundary layer thickness. This calculated value of G is now checked against the assumed desired value of G , and if not in sufficiently close agreement, another value of c_{m0} is assumed and the calculations are repeated until the difference between the assumed and calculated values for G is sufficiently small.

Following this, values of G for the passages between the stream surfaces for which the meridians were originally assumed are calculated using Equation 4 with suitable limits of integration corresponding to the stream surfaces. By trial and error in assumption of these limits of integration, corrected values for the intersections of the meridians with the assumed orthogonals may be determined, and so there may be plotted a new set of meridians and in turn a new set of orthogonals thereto. Then all of the above calculations are repeated until convergency is secured to a condition of securing calculated values sufficiently close to those assumed.

Once c_m is known, it is possible to calculate, using the usual methods, all flow properties which are of interest, such as pressure rise along the flow path, Mach numbers corresponding to absolute and relative velocities, the complete picture of mass flow distribution, and, using Equation 6, the values of nc_L along each meridian.

$$\left(\text{Note that } \frac{dz}{dl} = \cos \lambda. \right)$$

It will be noted that c_m , c_u , c , wr , the relative velocity w and the angle γ are all related in accordance with the vector diagram shown in Figure 12. λ is known from the meridian shapes finally found.

A plot of nc_L against l should give a flat topped curve smoothly dropping to zero at its ends corresponding to the inlet and outlet, as illustrated in Figure 14. If such shape of this curve is not found, then the assumptions as to work distribution, Figure 11, should be changed and the calculations repeated.

The number n of blades required may be determined from the value of nc_L , assuming a safe maximum value for c_L , the local lift coefficient, e.g. 1.0 for an impeller and 0.5 for a diffuser.

From Equation 5, which defines the variation of ϕ with l along a streamline, ϕ may be obtained by integration, ϕ being the wrap angle of the streamline S illustrated in Figure 7. The validity of Equation 5 will be apparent from consideration of Figures 8 and 12.

Plotting ϕ against l or z for various streamlines, three of which are illustrated in Figure 13 in plots of ϕ against

z, there is now secured the basis for fixing the actual physical construction of the blades.

Actual vanes must lie along streamlines to afford guidance of the flow in the direction of the streamlines. The physical vanes, which, of course, have substantial thickness, may be regarded as constructed on mean surfaces which are defined by a set of streamlines belonging to the different stream surfaces ranging from the hub contour to the tip contour. Vanes of maximum strength would be those constructed on vane surfaces which were radial from inlet to outlet. In accordance with the above principles this end cannot be secured but rather there are provided vanes which are as nearly radial as can be attained consistent with the design principles. The departure from a purely radial vane, the mean surface of which consists of radial lines, is limited by two considerations: (a) The vane must not be subject to destructive centrifugal stresses at the normal high speeds of desired operation; and (b) the departure from radial condition is assumed to be small in the derivation of the calculation procedure above outlined. It may be pointed out that departure from radial condition may be taken into account in the calculation procedure and under some conditions will improve the flow. Of special interest is the case of an approximation to what may be called an orthogonal flow channel for which the blade sections taken normal to the relative flow direction are orthogonal to the stream surfaces from the hub to the tip contours. Such orthogonal vanes have the property of requiring minimum lift forces to accomplish a desired work input and pressure rise and therefore lead to a maximum efficiency. With such vanes departure from vortex flow exists, and for the attainment of this end calculation procedures may be adopted similar to those described above for the case of true vortex flow.

As will be evident, the origin for measurement of ϕ is arbitrary and consequently the streamlines as illustrated in Figure 13 may be displaced angularly in the direction of ϕ to secure a condition such as illustrated in Figure 13. In this plot the streamlines may be brought into coincidence at some such common point as is indicated at A and under these conditions it will generally be found that the streamlines on this plot will also substantially coincide with each other at some other point or limited region such as indicated at B. It accordingly becomes possible in many cases, as in the case of the impeller blading of Figures 2 and 3, to provide single vanes extending from inlet to outlet which have two portions either accurately or approximately lying along radial lines as, for example, at A and B of Figure 13 while at the same time departures from radial condition are minimized at other locations along these vanes.

In other cases, however, where the streamlines have considerable departures from each other, attainment of conditions as illustrated in Figure 13 is not possible. The vanes may be split into two or more sections as illustrated in Figures 4 and 5 in which case each of the sections in itself may be caused to have one or more radial portions with minimum departure of the other portions of the section from radial condition. The several rows of blade sections thus provided are desirably secured end to end to each other to provide mutual support by welding or brazing.

The design procedure described above was applied to orthogonals distributed throughout the lengths of the streamlines from inlet to outlet as illustrated in Figure 9. However, without material departure from the principles involved the design procedure may be applied to orthogonals restricted to the inlet edge of a vane as at P_1 , P_2 and P_3 of Figure 13 and an orthogonal not substantially spaced from the inlet involving, for example, the points Q_1 , Q_2 and Q_3 illustrated in Figure 13 and along similar orthogonals at and adjacent to the outlet ends of the vanes. Under these conditions the vane shapes between these groups of orthogonals may be

somewhat arbitrarily assumed, nevertheless with a work input distribution essentially corresponding to that illustrated in Figure 11 and a lift coefficient distribution essentially corresponding to that in Figure 14. Departure from strict vortex flow, of course, is involved in this variation of design but vanes are secured which are unloaded at their leading and trailing portions. The unloading of the leading and trailing portions of the vanes is readily accomplished by starting and ending the streamlines in Figure 13 with a zero curvature in the case of such impellers as are illustrated in Figures 2 to 5 where the flow at the inlet and outlet has no more than a small radial component. In following the last mentioned procedures an approximate mean streamline can be found since c_m of the mean streamline is approximately fixed merely by considerations of continuity. Using this mean streamline as a guide and the slopes and curvatures resulting from calculations at the inlet and outlet there may be secured a vane shape which is reasonable for both manufacturing and stress. As previously noted such a vane will involve departure from the originally assumed vortex flow.

In summary of the above it may be pointed out that there are provided in accordance with the foregoing elastic fluid passages disposed about an axis and bounded by interior and exterior surfaces of revolution, the meridian lines of at least one of which surfaces deviate substantially from parallelism with the axis, and vanes for directing the elastic fluid along flow lines having a skew relation to the axis, the surfaces of the vanes conforming substantially to the flow lines adjacent thereto and definable by substantial conformity at any point of a vane to the Equation 5 of Figure 15 which defines the variation of wrap angle of a vane along a streamline at any point thereof when the expressions therein are defined by Equations 1 to 4 inclusive, and the procedure outlined above. It will be noted that despite the breaking up of streamlines into possible segments, when a complete vane consists of more than one section, the value of the angle γ is maintained at every point of a blade or vane element, the total of these angles thus defined being completely definitive of every portion of the blade.

The word "skew" is herein used in the mathematical sense of non-confinement to a plane, particularly, herein, to a plane through the axis of rotation of the rotor. It relates to a line the definition of which requires three dimensional coordinates expressive of position in space. It has the usual significance of indicating a twist about an axis more general than would be expressed by reference to a helix of uniform lead.

It will be understood that the invention is not limited to precise conformity with theory, and intentional deviations might sometimes be desirable, particularly to minimize stresses or to secure, for example in the case of the junction of two vane sections, a common welding edge of as long an extent as reasonably possible.

If the angular velocity ω were set at zero, it would appear that the foregoing method of design should apply to stationary passages as well as to rotating passages. However, if this were done directly in the above procedure, Equation 2 of Figure 15 would become indefinite. Consequently, this must be bypassed by assuming, instead of an N versus l distribution as in the case of an impeller, a $(c_u \cdot r)$ versus l distribution, c_u being calculated from this. The last mentioned curve is assumed of a form similar to the curve in Figure 11 but of opposite slope. Except for this change in procedure the method of design of a diffuser remains the same as for an impeller.

In view of the above it will be unnecessary to describe the corresponding steps for diffuser design but it may be generally pointed out that the diffuser vanes, like the impeller vanes, are caused to conform to the current streamlines which may be displaced and broken up into

segments to provide the most advantageous mechanical construction.

It may be here noted that all of the foregoing matters apply not only to mixed flow impellers but to axial flow impellers and to centrifugal impellers having radial discharge, leading in both of the last cases to improvements in efficiency.

By reason of the fact that the foregoing procedure derived the blade shapes by a method of successive approximations, a final expression of ϕ or γ explicitly in terms of assumed constants was not obtained. However, by making certain approximations, there may be obtained for γ the expression given in Equation 7 of Figure 15 in which ω , r , $(c_u \cdot r)_{in}$, $(c_u \cdot r)_{out}$, and G are as heretofore defined while, referring to Figure 16, the other quantities therein may be defined as follows:

ST is a mean line (not a meridian of a stream surface, though usually it will approximate such a meridian) extending midway between hub and tip meridians in a common axial plane. Considering any point P in such plane, UV is an orthogonal to the meridians of the stream surfaces, including the hub and tip meridians, which passes through P. UV is then the intersection with said axial plane of a surface of revolution orthogonal to the streamlines and stream surfaces.

Let the total length of ST be l_1' , and let l_1 be the distance measured along ST from S to the orthogonal UV. Let Δn be the total length of UV from the inlet to the outlet ends of the vanes and let n be the spacing of P from ST measured along UV.

Let k_0 be the curvature of the hub meridian at U and let k_1 be the curvature of the tip meridian at V, taken in the sense previously stated.

$$k_A = \frac{k_0 + k_1}{2}$$

$$\Delta k = k_1 - k_0$$

$$m = \frac{l_1}{l_1'}$$

a or b is arbitrary but subject to the condition $a+b=2$, both a and b being positive.

α and β are given by the relations: $1 \leq \alpha \leq 2$, $1 \leq \beta \leq 2$.

v_1 = the average specific volume at the inlet.

v_2 = the average specific volume at the outlet.

A = the area of a surface through P and normal to the stream surface meridians between the hub and tip contour surfaces.

Equation 7 gives a very close approximation at every point to γ as calculated by the method of successive approximations given heretofore, and may be used as an analytical definition of the blade surfaces in terms of their component streamlines. Through Equation 5 and a suitable displacement of the streamlines in accordance with the description given above with reference to Figure 13 to achieve approximately radial conditions, the actual blade surfaces may be derived therefrom.

As will appear from the foregoing, vanes may be provided in many instances which are very nearly radial except at their inlet and outlet portions but which, nevertheless, will provide substantially the desired characteristics of flow with proper blade loading with a fair degree of approximation to vortex flow. In accordance with known principles of aerodynamics deviations of flow may be produced by vanes without detrimentally affecting the overall results to be accomplished. Accordingly, impeller vanes may be rather simply defined in still another fashion conforming rather closely to the definitions heretofore set forth.

Figure 17 will serve to make clear this form of definition. In this figure, referring to Figure 8, there are plotted two typical curves, designated S_A and S_B , for streamlines S on a graph having as ordinates $y = \int r \cdot d\phi$ and abscissae l . In such a plot, at any point P of a streamline corresponding to P of Figure 8 the slope of the streamline curve is

$\tan \gamma$, the curve, therefore, being a true-angle true-distance projection of the streamline. The curve S_A is typical of such plot for a streamline of an impeller for which the prewhirl at the inlet is different from zero and the pressure ratio is of the order of 2. The curve S_B is typical of such plot for a streamline of an impeller for which the prewhirl at the inlet is substantially zero and the pressure ratio is of the order of 3. For any streamline, hub, tip or intermediate, such curve has, for vanes provided in accordance with the present invention, an S-shaped form from the inlet to the outlet in which the curvature changes from a negative value, through zero, to a positive value, i.e. at the inlet

$$\frac{d^2y}{dl^2}$$

is negative, and at the outlet

$$\frac{d^2y}{dl^2}$$

is positive, and this form is characteristic of such vanes. It should be noted that a theoretical vane of infinitesimal thickness would follow a group of streamlines. On such a theoretical vane there is patterned the actual vane which must have actual thickness generally varying from hub to tip, the actual vane therefore having as its mean surface the theoretical vane. Such an actual vane would generally have an airfoil section. This should not be confused with what has just been described an airfoil vane, the midline of which would not have the reversal of curvature above noted. Such a vane, it is true, generally has a reversal of curvature of one of its actual faces, but this is not the same as the matter of vanes built upon, or having as a mean surface, a surface made up of streamline elements having reversed curvature as described.

Here again the matters just described also apply generally to diffuser blades which are fastened to the casing. Since they are not subjected to centrifugal loads there is less restriction on this from the standpoint of stresses and hence substantial departures from radial condition may be tolerated.

From the foregoing it will be evident that the blade or vane shapes for impellers and diffusers are three dimensional and of such form that in general machining would be prohibited, this same applying also to the blades defining turbine passages. Accordingly, a novel procedure is adopted for forming these and for attaching them to rotors or casings. This procedure involves die-forming the vanes from the proper metal (generally steel) from blanks of flat type which may be preliminarily machined to provide desired tapering and faired leading and trailing edges. Thin metal may generally be used merely sufficiently thick to provide the necessary rigidity and strength for resistance of stresses. These blanks may also be provided with enlarged edge portions to provide the root sections of the vanes which generally have a width three or four times the average vane thickness. The vanes so formed are then secured to the machined supporting surface of the impeller or casing either by copper furnace-brazing or by flash welding, both of which are carried out in accordance with conventional practices. In the case of copper brazing all of the vanes may be secured to a rotor or casing simultaneously. Copper brazing in this fashion has been found to be extremely satisfactory, giving quite adequate strength even in the case of rotor assemblies required to operate at extremely high speeds.

Steel vanes have good fatigue characteristics, and since they may be made quite thin they will have a low natural frequency of vibration with the result that effective damping is secured limiting amplitudes of vibration within safe stress conditions.

As has been previously indicated the rotor (of the particular embodiment of the invention shown by Figure 5), considering all of the stages except the fifth stage, is essentially a body of revolution the outer contour of which has the smooth approximately sinusoidal character indicated

in the drawings. The total contour is made up of the individual rotors of stages 1 to 4, inclusive, which have similar characteristics and involve similar principles of design so that only one typical stage need be described. As has been indicated the rotor of each of these stages comprises a pair of radial discs connected by a tubular cylinder and providing the support for the outwardly convex shell to which the impeller blades are secured and which also provides the inner bounding surface of the diffuser of its stage. Except for the presence of the blades the impeller and diffuser portions of the shell are quite similar in structure, and, in fact, for convenience of construction may be made exactly the same so that each rotor is symmetrical about a radial plane passing through the portion of its periphery at maximum diameter. Because of the centrifugal load of the blades which it carries the impeller is usually more critically stressed than the diffuser and in the case of adoption of a symmetrical arrangement there merely results a diffuser portion of the rotor which is somewhat stronger than required. If equal stressing of the impeller and diffuser portions of the rotor is desired, a suitable unsymmetrical form of the rotor will result. It is, of course, advantageous to use such an arrangement of the rotor when aerodynamic and other circumstances permit.

The basic principle involved is that of providing a relatively thin flexible shell having a general form which satisfies the aerodynamic requirements and at the same time serves as a principal structural member capable of supporting its own centrifugal load plus the centrifugal load of the blades. In order to make the shell as thin and light as possible it is necessary to minimize shear and bending stresses in this part and to design it to be supported mainly by simple membrane stresses acting in the circumferential and meridional directions.

In particular to prevent the circumferential stress from exceeding safe limits in supporting a given centrifugal load it is necessary to insure that a sufficient proportion of this load will be sustained by the meridional stresses. This is accomplished by having the ends of the rotor shell anchored to the stiff frame consisting of the axial tube and the two radial discs.

In order that the shell may be of light construction, only membrane stresses should be permitted to occur therein. It will be evident that the inward resultant of the circumferential and meridional stresses is due respectively to the inward curvature of the membrane in these two orthogonal directions. The curvature in the circumferential direction is merely the reciprocal of the radius, and therefore, the greater the radius the less will be the circumferential curvature. Furthermore, the greater the radius the greater will be the centrifugal load of the shell and blades. Consequently, the portion of the total load which must be supported by the meridional stresses is the greatest at the greatest radius and decreases with a decrease in radius. The curvature in the meridional direction, therefore, varies so as to be maximum at the maximum radius, decreasing on either side. Each side of the shell gradually approaches a relatively straight, approximately conical shape, and at the innermost radii may even begin to curve outward, as illustrated, to cause the outer contour of one stage rotor to merge with that of the next one.

Since the resultant of the centrifugal load and the tangential force on an element acts exactly in the radial direction, it is clear that the resultant of the two meridional forces must also act exactly in the radial direction. Hence, the axial components of the meridional forces on both sides of any element must be exactly equal and opposite. This means that the axial component of the meridional force is a constant all along the shell.

With the axial component constant, it follows that the resultant meridional force increases with the angle of inclination of the shell; hence, it is a minimum at the crown where the shell has no inclination and increases

rapidly toward each end. It is usually most convenient for construction purposes to make the outer portion of the shell of uniform thickness, but because of the increase of meridional force with shell inclination a point 5 may be reached where it becomes necessary to allow the shell thickness to increase in order to prevent excessive meridional stresses. This effect is accentuated by the fact that the decrease in radius toward the ends of the shell requires a further increase in thickness in order to maintain sufficient cross sectional area. Hence, there are in 10 general two sections of the shell: the outer part where the thickness is held constant and the meridional stress increases, and the inner part where the meridional stress is held at or below some limiting value while the thickness is allowed to increase correspondingly. In particular 15 cases, one or the other of these regions may not occur. The thickness may, for example, be allowed to increase continuously from the maximum radius to the minimum radius. But more commonly the meridional stress may 20 remain within safe bounds all the way to the minimum radius without requiring any increase in thickness of the shell. The increase in thickness generally occurs in the ends of the rotor merely as a consequence of fairing of the contour required for aerodynamic reasons and is simply 25 in the nature of a fillet added to the outside of the shell to join it smoothly to the overhung edge beyond the end discs. As long as it is confined to the lower end of the shell near the junctions of the shell, the tube, the discs and overhung edge, it has no major effect on the 30 stress distribution in the critical outer region. In general the parts of the rotor which extend outside the tube and discs influence the shell proper only in so far as they actually load the discs and affect their deflections. Hence, 35 alternative forms of construction may be employed for these parts without greatly affecting the design of the central portion of the shell.

If the shell with its blades were not anchored at its ends to a stiffening frame consisting of the tube and discs, it would not sustain any meridional stresses. Consequently, 40 the centrifugal load would have to be supported wholly by the circumferential stresses which would then be correspondingly high. Under this type of stress distribution the shell would undergo a relatively high radial expansion and axial shortening. The tube and discs too 45 would undergo some radial expansion and axial shortening, but if they were not loaded by attachment to the shell these deflections would be small compared with those of the shell. Since in the actual rotor the two ends of the shell and frame are physically connected, this difference 50 in deflections cannot exist and hence there must be acting at these points a set of internal forces to reconcile the deflections. In particular, the axial component of the total end force is transmitted all along the shell and is everywhere constant as was pointed out above. It is this component which determines the amount of support the shell receives in the meridional direction, and hence also the remaining load which must be sustained by the circumferential 55 stresses.

The tube such as 48 in Figure 3 which is under compression will generally be cylindrical although if the two 60 ends of the rotor have different radii the tube may be conical in form or may be replaced by a number of separate struts having suitable cross sections. If a number of stages are employed, it is desirable that the tubes of the successive hubs should be in alignment since this 65 gives a considerable overall rigidity against lateral deflections and vibrations. The tube must sustain an axial compressive force equal to the axial component of the tensile force on a shell where it joins the tube plus the compression imparted by the tie rod such as 12 which 70 extends through the rotor. This tube must also sustain a circumferential stress due to the centrifugal forces on it.

Since the individual blades are closely spaced around the periphery of the shell, the centrifugal load of the 75 blades may be assumed to be uniformly distributed

15

around the circumference of the shell. This total circumferential load may vary along the axis depending upon the particular dimensions of the blades at various axial positions.

The determination of the proper shell shape involves taking the foregoing considerations into account, and performing step-by-step calculations, considering as a fundamental matter the desire to have every element of the shell subject solely to tensile forces acting tangent to a mean surface of the shell. These calculations are carried out in accordance with the usual principles for solving stress problems, and need not be described in detail. In brief, the result may be stated to be the attainment of a rotor or hub construction comprising a member extending in the direction of and symmetrical about the axis of rotation, and in itself a body of rotation, which is under compression, and which together with the radial end discs provides an anchor for a convex shell in the form of a surface of revolution which is stressed substantially only in tension when loaded with blades. As will be pointed out hereafter, the axial strut member 48 and the end discs 44 and 46 need not necessarily be so rather well defined from each other as they are in Figure 3, but radial and axial support may be attained through an alternative relatively rigid central portion of the hub of which an example appears in Figure 20. In this last case, as will be described hereafter, the same rotor having a shell construction supports both compressor and turbine blades.

In the foregoing, little has been said about the applications of the principles of the invention to turbines. It will be evident that what has been described is directly applicable to turbine construction in which the design of the turbine blades may be carried out using the same principles as those forming the basis for design of compressor blades or vanes merely taking into account the fact that energy is delivered by the driving fluid to the turbine shaft through the medium of the blades rather than the reverse, so that the vortex strength at the inlet is greater than the vortex strength at the outlet. The nozzles for such a turbine involve design considerations somewhat similar to those involved in the design of the diffuser vanes but taking into consideration the fact that the vanes which define the nozzle passages must give rise to vortex flow suitable for admission at the inlet ends of the turbine rotor passages. The hub construction of a turbine rotor may also be quite similar to the hub construction for a compressor, here again so designing the hub that the shell thereof will be only under tensile stresses of the type involved in a membrane, i.e. tangent to the mid-surface of the shell. While the invention is accordingly applicable generally to gas or steam turbines, the considerations involved in the application of the invention to turbines will best become apparent from consideration of two examples of gas turbines illustrated in Figures 18, 19 and 20. The resulting gas turbine units have particular advantages which also will now be pointed out.

Referring first to Figures 18 and 19, there is illustrated therein a gas turbine power plant which is particularly suitable for substantially constant speed operation as for the driving of generators, blowers, or the like. A shaft 102 is mounted in a bearing indicated at 110, and at its left-hand end is splined to the interior of a pinion 108 of a reduction gearing system enclosed in a casing 109 and having projecting from it a coupling 111 for the delivery of useful power. The pinion 108 is mounted in bearings 104 and 106.

The shaft at its right-hand end is provided with a hub comprising the radial discs 112 and 114, the axial cylindrical shell 116 and the annular shell 118 which is of the catenoid type heretofore described in connection with compressors. This shell 118 when loaded with compressor and turbine blading, as will be presently indicated, has all of its parts under tension and accord-

16

ingly may be made quite thin and light notwithstanding the provision of adequate strength for operation at high speeds and, on the turbine side, high temperatures. A compressor is provided by vanes 120 carried by the hub and designed in accordance with the principles heretofore described in detail. These vanes receive air from the inlet passage 122 and discharge the compressed air into the passage 123 which at 124 is provided with diffuser vanes 124 which are also desirably designed in accordance with the foregoing principles. The compressed air enters an annular passage 125 from which it is delivered through openings 126 associated with guiding louvres into an annular combustion chamber 128 to which fuel is introduced for combustion through nozzles 130, which direct the fuel spray substantially tangentially in the direction of rotation in such a manner that the largest possible flame travel is obtained, there being provided suitable igniting means, not shown. The products of combustion flow through nozzle passages defined by blades 132 also designed in accordance with the principles heretofore mentioned, and flow then takes place in the form of a free vortex in the region 134 which directs the gases into the turbine passages defined by blades 136 carried by the hub. These blades are also designed in accordance with the principles above mentioned. As will be evident, the gases have both radially inward and axial components of flow, as well as circumferential components of flow, through the turbine passages and are discharged into the region 138 followed by suitable blading 140 from which discharge is effected into the discharge passage 142. The fixed blading at 140 may be so arranged as to provide, by reducing the spin of the gases, a rise of pressure to the discharge pressure in the passage 142 so that if this discharge occurs to the atmosphere, sub-atmospheric pressure may exist in the region 138 of discharge from the turbine passages.

As illustrated particularly in Figure 19, the blades 136 of the turbine have a hollow form, each being made of two halves of sheet metal which are seam welded together along the entrance edge and along the tip contour leaving only the discharge edge open. Passages 144 communicate with the compressor passages so that compressed air may flow therefrom into the interior of the rotor shell, this air being discharged through passages 146 into the interior of the turbine blades from which it is discharged at the open ends of these blades to mingle with the discharged driving gases. As a result of this construction, effective cooling of the rotor shell is provided and also cooling of the turbine blades to maintain them at a safe temperature.

Before proceeding to describe the characteristics of operation and advantages of this gas turbine, reference will first be made to Figure 20 which shows a somewhat similar gas turbine having various features in common with that which was just described, but adapted for variable speed operation, this turbine being particularly useful for application to marine, locomotive and automotive propulsion.

A hollow shaft 148 supported in shaft bearings carries the hub 150 of a combination compressor and turbine, which hub is provided in the form of a shell in the form of a solid body of revolution having the characteristics previously described. This hub, it will be noted differs somewhat from the hubs previously described in that its portions which may be considered the end discs merge continuously with the shell without the provision of any axial cylindrical strut spaced substantially from the axis of rotation. In this case, the end discs merge closer to the axis of rotation and are of a form, due to the large interior fillet construction, to provide sufficient axial rigidity to withstand the axial stress imparted by the convex shell. The same principles, of course, apply to this hub as to the hubs previously described.

The hub portion 152 of the hub 150 carries compressor blading at 154 constructed in accordance with the

principles heretofore set forth in detail, the complete compressor being formed by these blades and the housing receiving air from the inlet duct 155, and discharging it into the vaneless portion 156 of the diffuser and then into the vaneed portion of the diffuser containing the vanes 158 also of the type previously described. The air is discharged from the diffuser into chamber 160 whence it passes through the tubes 162 into the chamber 164, and returns through the tubes 166 into the chamber 168. From this chamber the air passes through the openings 170 into the combustion chamber 172 into which fuel is introduced through the fuel nozzles 130. The products of combustion pass through the nozzles formed by nozzle vanes 174 and the passage 176 to turbine rotor passages which are defined by vanes 178 desirably of the hollow type described above in connection with Figures 18 and 19. These blades 178 are carried by the hub 150.

In the present turbine, a second stage is provided by blading 180 which may be constructed in accordance with the principles heretofore indicated, carried by a hub 182 supported by a shaft 184 which passes through the hollow shaft 148 and is supported adjacent to the hub 182 by a bearing 186 inside the hub 150, and at its other end by a suitable bearing (not shown) in the reduction gearing assembly 188 through which reduction gearing the shaft 184 drives the output shaft 190. The turbine passages defined by the blades 180 discharge the gases into the passage 192 provided with blades 194 similar to blades 140 described in connection with Figure 18. From the blades 194 the gases pass to the shell 196 whence they flow over the tubes 166 and 162 to provide heat exchange with the compressed air approaching the combustion chamber. Discharge from the heat exchanger is effected at 198.

Cooling of the rotor 150 and of the turbine blading 178 carried thereby is effected in the same fashion as that previously described by bleeding compressed air from the compressor through the openings 200 into the interior of the rotor shell, and thence through the openings 202 into the interior of the hollow blades 178.

Additional cooling is effected in the designs shown in both Figures 18 and 20 by air bypassing over the crowns of the rotors, the partitions beyond these crowns "peeling off" air from the compressor flows and directing the air in work-yielding fashion into the turbine passages.

In the arrangement illustrated in Figure 20, it will be evident that the compressor and first stage of the turbine constitute a rotary unit which is mechanically independent of the second stage turbine which delivers the useful output from the power plant. Accordingly, the compressor and its associated driving turbine run at a speed dictated by the load, and entirely independent of the second stage power turbine which furnishes all of the useful power output. Inasmuch as both the compressor driving turbine and the power turbine rotate in the same direction, there is little or no differential speed between the two during normal operation. Only during the starting of the plant does the condition of maximum difference in speed between the two turbines exist since at that time when the power turbine is standing still the compressor and its turbine may be operating at full speed. In view of this fact, the bearing at 186 does not present a difficult problem of design and may be of a conventional high speed type.

In view of the fact that the compression ratio obtainable with good efficiency by means of a single stage compressor is limited, the thermal efficiency is considerably improved by resorting to exhaust heat recovery through the use of the heat exchanger which has been described, since then higher initial temperatures may be effectively used. However, where space saving is highly desirable, the heat exchanger may be omitted, the compressed air being delivered directly to the combustion chamber as in the modifications illustrated in Figure 18.

The gas turbine plants of the type illustrated in Figures 18 and 20 have the great advantage of maximum simplicity which is particularly apparent in the case of the type of plant illustrated in Figure 20, in which the 5 nested arrangement of the turbine shafts permits the direct flow of driving gases from the first stage to the second stage, the blading of these stages being so designed in accordance with the principles given above that the vortex flow from the first stage is directly received by the second stage without any substantial loss of energy. In addition to this general advantage, there are further advantages as follows:

All surfaces of the rotor are working surfaces eliminating the windage and friction losses normally associated 15 with compressors and turbines. The elimination of these losses substantially increases turbine and compressor efficiencies.

Excellent cooling of the turbine and its blading is obtained by direct cooling by heat transfer through the 20 metal of the hub from the turbine to the compressor and also by the automatically forced circulation of the air introduced within the convex shell. It may be pointed out that instead of having air circulation take place from the impeller through the interior of the shell and 25 into the turbine blading, heat transfer may also be effected by having the convex shell completely closed and filled with compressed hydrogen or another gas having similar high heat transfer characteristics.

Cooling is further effected by the thin layer of air by 30 passing directly over the crown of the rotor shell from the compressor side to the turbine side through the clearance space about the periphery of the shell. This effectively prevents the hot gases from contacting the turbine side of the rotor hub. The internal turbine blade cooling is effected by air bled from the compressor to the 35 inside of the shell and thence to the inside of the turbine blades, this air discharging all along the discharge edge of each hollow blade.

By the application to the turbine design of the aero- 40 dynamic principles, discussed at length with particular reference to compressor blading, the highest possible turbine efficiency is obtained. In the case of the compressor, the heretofore mentioned principles aid, among other things, to obtain a substantial part of the pressure 45 rise by means of the centrifugal effect. Conversely, in the case of the turbine, a substantial percentage of the energy handled by the turbine is caused by expansion against the centrifugal field, which part of the energy is converted with one-hundred percent efficiency into mechanical energy. The turbine may, therefore, be aptly 50 described as a centripetal vortex turbine.

Another advantage of the constructions illustrated is that the stationary parts exposed to high temperature are 55 completely surrounded by air discharging from the compressor so that the unit will be exteriorly relatively cool with the heat exchange which does occur being between the high temperature gases and the air approaching the combustion chamber so as to provide desirable heating of this air.

60 What is claimed is:

1. An elastic fluid mechanism including a rotor comprising a hub member and vanes carried thereby, said hub member including a substantially rigid inner portion, said inner portion comprising a pair of radial end discs joined and held spaced at their peripheries by rigid 65 strut means capable of sustaining axial compression stresses, and a hollow and relatively flexible shell having as its mean surface a surface of revolution which is throughout its extent outwardly convex, said shell being integral with said radial end discs and having a thickness increasing from its maximum diameter to its junctions with said radial end discs, said shell carrying the vanes and being shaped so that its walls are substantially only under tension under the action of centrifugal forces.
- 70 2. A compressor for elastic fluid including a rotor hav-

ing a hub member of increasing radius from its inlet towards its outlet, and vanes carried by the hub member and a housing surrounding the vanes and cooperating with the vanes and the hub member to define elastic fluid passages, said vanes having throughout said passages their surfaces shaped to coincide with flow lines of said fluid, which fluid has a flow such that at every point of any section of said passages orthogonal to the flow there is a substantially constant product of the whirl component of flow times the radius.

3. A compressor according to claim 2 in which the vanes comprise a plurality of sets axially succeeding each other.

4. A compressor according to claim 2 in which each of the vanes has at least one portion which is substantially radial with respect to the rotor axis.

5. A compressor according to claim 2 including inner and outer walls and spin-reducing stationary vanes located therebetween to define passages providing continuations of the first mentioned passages and receiving directly from the first mentioned passages elastic fluid having spin due to flow through the first mentioned passages, said spin reducing vanes having throughout the second mentioned passages their surfaces shaped to coincide with flow lines of said fluid, which fluid has a flow such that at every point of any section of said second mentioned passages orthogonal to the flow there is a substantially constant product of the whirl component of flow times the radius.

6. An elastic fluid mechanism comprising members providing inner and outer surfaces of revolution having a common axis and vanes extending between said surfaces to define, with portions of said inner and outer surfaces, elastic fluid passages disposed about said axis, the meridian lines of at least one of said surfaces deviating from parallelism with said axis, and said vanes directing the elastic fluid along flow lines having a skew relation to said axis, the surfaces of said vanes conforming to the flow lines adjacent thereto and characterized by substantial conformity at any point of a vane to the equation

$$\tan \gamma = \frac{\omega r^2 - (c_u \cdot r)_{in} - \frac{1}{2}[(c_u \cdot r)_{out} - (c_u \cdot r)_{in}] \left[a \left(1 - \cos^2 \frac{m\pi}{2} \right) + b \cdot \sin^2 \frac{m\pi}{2} \right] \cdot A}{[v_1(1-m) + v_2m] \left[e^{-k_A n + \frac{\Delta k}{2\Delta n} n^2} \right] rG}$$

in which:

γ is the angle at said point which the vane makes with respect to the meridian of the surface of revolution through the flow line at the point measured in the tangent plane to the last mentioned surface at the point;

ω is the angular velocity of the vanes;

r is the radius at the point;

$(c_u \cdot r)_{in}$ is the vortex strength at the inlet;

$(c_u \cdot r)_{out}$ is the vortex strength at the outlet;

m is equal to

$$\frac{l_1}{l_1'}$$

l_1' being the total length between the inlet and outlet ends of the vane of a mean line extending midway between radially related meridians of said inner and outer surfaces of revolution, and l_1 being the distance measured from the inlet end of the vane along said mean line to a surface of revolution through said point orthogonal to said inner and outer surfaces of revolution;

Δn is the total length of the intersection with an axial plane of said orthogonal surface of revolution between said inner and outer surfaces of revolution;

n is the length measured in an axial plane through said point to the point from the circle of intersection of said orthogonal surface of revolution and a surface of revolution through said mean line along the intercept of

said axial plane with said orthogonal surface of revolution;

$$k_A = \frac{k_0 + k_1}{2} \text{ and } \Delta k = k_1 - k_0$$

5 k_0 being the curvature of a meridian of said inner surface of revolution at its intersection with said orthogonal surface of revolution, and k_1 being the curvature of a meridian of said outer surface of revolution at its intersection with said orthogonal surface of revolution;

10 e is the base of natural logarithms;

v_1 is the average specific volume of the elastic fluid at the inlet;

15 v_2 is the average specific volume of the elastic fluid at the outlet;

A is the area between said inner and outer surfaces of revolution of a surface through the first mentioned point and normal to the meridians of the surfaces of revolution through the flow lines;

20 G is the weight flow of the elastic fluid;

a and b are positive constants related by the relation $a+b=2$; and

α and β are constants, of which $1 \leq \alpha \leq 2$ and $1 \leq \beta \leq 2$;

25 Said vanes having their maximum aerodynamic loading between their inlet and outlet ends.

7. An elastic fluid mechanism in accordance with claim

6 in which the member providing the inner surface of revolution is a rotor rotating about said axis, and in which the vanes are carried by the rotor.

8. An elastic fluid mechanism in accordance with claim 7 provided with means for driving the rotor to impart energy to the elastic fluid.

9. An elastic fluid mechanism in accordance with claim 7 provided with means for directing the elastic fluid at

35 high velocity to said vanes to drive the rotor.

10. An elastic fluid mechanism in accordance with claim 6 constituting a diffuser for a rotary compressor in which said vanes are stationary, ω being zero.

11. An elastic fluid mechanism comprising members 40 providing inner and outer surfaces of revolution having a common axis and vanes extending between said sur-

50 faces to define, with portions of said inner and outer surfaces, elastic fluid passages disposed about said axis, the meridian lines of at least one of said surfaces deviating from parallelism with said axis, and said vanes directing the elastic fluid along flow lines having a skew relation to said axis, the surfaces of said vanes conforming to the flow lines adjacent thereto and characterized by substantial conformity at any point of a vane to the equations.

60 (A)

$$\frac{c_m}{c_{m0}} = e^{-k_0 s - k_1 s^2}$$

(B)

$$c_u = \frac{1}{r} \left[(c_u \cdot r)_{in} + \frac{gJ}{\omega} N \right]$$

(C)

$$G = 2\pi r \int_0^{\Delta s} \frac{c_m r}{v} ds$$

(D)

$$\omega r - c_u = c_m \tan \gamma$$

(E)

$$nc_L = 4\pi e \frac{\cos^2 \gamma \cdot d(c_u \cdot r)}{c_m \cdot dl}$$

in which:

c_m is the meridian velocity;

75 k_0 is the curvature of the meridian of said inner sur-

21

face of revolution at the base of an orthogonal to surfaces of revolution through flow lines which orthogonal passes through the point;

s is the distance from the hub to the point measured along said orthogonal;

k_1' is equal to

$$\frac{k_1 - k_0}{2\Delta s}$$

in which k_1 is the curvature of said outer surface of revolution at its intersection with said orthogonal, and Δs is the total length of said orthogonal;

c_{m0} is the meridian velocity at the hub end of said orthogonal;

e is the base of natural logarithms;

r is the radius at the point;

$(c_u \cdot r)_m$ is the vortex strength at the inlet;

g is the acceleration due to gravity;

J is the mechanical equivalent of heat;

ω is the angular velocity of the vanes;

N is the work input reached from the entrance of said passages to the point;

c_u is the whirl component of the velocity of flow of the elastic fluid at the point as defined by Equation B;

G is the weight flow of the elastic fluid;

ϵ is the constriction coefficient;

v is specific volume;

The integral of Equation C is taken along said orthogonal;

γ is the angle at said point which the vane makes with respect to the meridian of the surface of revolution through the flow line at the point measured in the tangent plane to the last mentioned surface at the point, c_m in Equation D being evaluated at the point;

n is the number of said vanes;

c_L is the lift coefficient; and

$$\frac{d(c_u \cdot r)}{dl}$$

is the change of vortex strength at the point with respect to distance measured to the point from the inlet end of a vane along a meridian to the surface of revolution through a streamline through the point, c_m in Equation E being evaluated at the point, and nc_L having its maximum value between the inlet and outlet ends of the vanes.

12. An elastic fluid mechanism in accordance with claim 11 in which the member providing the inner surface of revolution is a rotor rotating about said axis, and in which the vanes are carried by the rotor.

13. An elastic fluid mechanism in accordance with claim 12 provided with means for driving the rotor to impart energy to the elastic fluid.

14. An elastic fluid mechanism in accordance with claim 12 provided with means for directing the elastic fluid at high velocity to said vanes to drive the rotor.

15. A diffuser for a rotary compressor, said diffuser comprising members providing inner and outer surfaces of revolution having a common axis and vanes extending between said surfaces to define, with portions of said inner and outer surfaces, elastic fluid passages disposed

22

about said axis, the meridian lines of at least one of said surfaces deviating from parallelism with said axis, and said vanes directing the elastic fluid along flow lines having a skew relation to said axis, the surfaces of said vanes conforming to the flow lines adjacent thereto and characterized by substantial conformity at any point of a vane to Equations C, D and E of claim 20 and the definitions of the terms of said equations in claim 20, said vanes being stationary, ω being zero.

16. An elastic fluid mechanism comprising members providing inner and outer surfaces of revolution having a common axis and vanes extending between said surfaces to define, with portions of said inner and outer surfaces, elastic fluid passages disposed about said axis, the meridian lines of at least one of said surfaces deviating from parallelism with said axis, and said vanes directing the elastic fluid along flow lines having a skew relation to said axis, the surfaces of said vanes conforming to the flow lines adjacent thereto and characterized by the fact that, γ being the angle at any point which the vane makes with respect to the meridian of the surface of revolution through the flow line at the point measured in the tangent plane to the last mentioned surface at the point, and l being the distance measured to the point from the inlet end of a vane along said meridian, a plot of y against l , defined by the relation

$$\frac{dy}{dl} = \tan \gamma$$

30 is a curve having a point of inflection between the inlet and outlet ends of the vane,

$$\frac{d^2y}{dl^2}$$

- 35 being negative at the inlet end and positive at the outlet end.

17. An elastic fluid mechanism in accordance with claim 16 in which the member providing the inner surface of revolution is a rotor rotating about said axis, and in which the vanes are carried by the rotor.

18. An elastic fluid mechanism in accordance with claim 17 provided with means for driving the rotor to impart energy to the elastic fluid.

19. An elastic fluid mechanism in accordance with claim 17 provided with means for directing the elastic fluid at high velocity to said vanes to drive the rotor.

20. An elastic fluid mechanism in accordance with claim 16 constituting a diffuser for a rotary compressor in which said vanes are stationary.

UNITED STATES PATENT OFFICE
CERTIFICATE OF CORRECTION

Patent No. 2,943,839

July 5, 1960

Rudolph Birmann

It is hereby certified that error appears in the printed specification of the above numbered patent requiring correction and that the said Letters Patent should read as corrected below.

Column 20, line 24, for "Said" read -- said --; column 22, lines 7 and 8, for the claim reference numeral "20", each occurrence, read -- 11 --.

Signed and sealed this 31st day of January 1961.
